His Attorney.

UNITED STATES PATENT OFFICE

2,663,851

LAMP LOCKING LAMPHOLDER FOR
TUBULAR LAMPS

John M. Pistey, Fairfield, Conn., assignor to General Electric Company, a corporation of New York

Application November 5, 1952, Serial No. 318,850

1 Claim. (Cl. 339—50)

1

The present invention relates to lampholders for tubular lamps of the single contact pin type and especially to the lampholder which holds the low voltage end of the lamp.

The object of the invention is to provide in a lampholder for a single contact pin type lamp an improved locking and releasing means for the contact pin which is simple in structure, reliable in use, and capable of being provided at low cost; and which is so arranged that the lamp end can be readily inserted and locked in position in the lampholder and released and removed from the lampholder by the use of only one hand, a thing of importance in connection with the use of such lampholders.

My invention relates particularly to lampholders of this type which comprise a pair of spring contact arms fixed in the lampholder housing at their inner ends, the lamp end contact pin being held between the free outer ends of the spring contact arms. According to my invention, I provide at the outer end of the lampholder housing at one side of the slot through which the contact pin is inserted into the lampholder, a pivoted locking finger made of insulating material, the inner end of which is in engagement with the inner side of one of the spring contact arms and is held by the spring contact arm over the contact pin to lock the pin in position in the lampholder, the outer end of the locking finger projecting beyond the end of the lampholder casing, the arrangement being such that turning the locking finger moves the spring contact arm to release the contact pin and permit the lamp end to drop out of or be easily moved out of the lampholder into the hand of the person removing the lamp.

In the drawing.

Fig. 1 is a side view showing a tubular lamp mounted at its left-hand end in a high voltage lampholder and at the other end in a low voltage lampholder embodying my invention.

Fig. 2 is a sectional view taken on line 2—2, Fig. 1.

Fig. 3 is a sectional view taken on line 3—3, Fig. 2.

Fig. 4 is a bottom planed view of the lampholder.

Fig. 5 is a detailed view illustrating the manner of releasing the lampholder locking means and removing a lamp end using only one hand.

Referring to the drawing, 1 indicates a tubular lamp having the contact pin 2 at its one end mounted in a lampholder 3 and the contact pin 4 at its other end mounted in a lampholder 5 embodying my invention.

2

Lampholder 3 may be of any suitable construction. It is shown as comprising a housing 6 provided with a spring contact arm 7 with which contact pin 2 engages, the pin being inserted through an opening in the inner side wall of the housing.

Lampholder 5 comprises a housing having an inner side wall 8, an outer side wall 9, a top wall 10 and end walls 11 and 12. At its lower end are walls which define a terminal chamber 13. Attached at their lower ends in terminal chamber 13 is a pair of contact arms 14 and 15 which extend up through the housing to a position adjacent the under side of top wall 10; and in top wall 10 and inner side wall 8 is a slot 16 through which a contact pin on a tubular lamp end may be inserted to a position between the ends of the two contact arms. On the inner surface of wall 8 adjacent the lower end of slot 16 is a projection 17, the opposite sides of which form stops to limit movement of the contact arms toward each other and which, along with the bottom end of slot 16, forms a curve seat for a contact pin. Contact arms 14 and 15 are formed from spring strip material and contact arm 14 is constructed and arranged to be biased toward contact arm 15. They are shown as being fixed in the terminal chamber by screws 18 and as being provided with terminal screws 19. Contact arm 15 is provided with a seat 20 for a contact pin. The contact arms are forced under tension against projection 17 by lugs or wings 21 formed integral with contact arms 14 and 15, the outer ends of which engage the inner surfaces of walls 11 and 12.

Pivotedly mounted on a pivot pin 22 which extends across a slot 23 in top wall 10 at the side of slot 16 adjacent contact arm 14 is a curved locking and releasing finger 24. The inner end of finger 24 projects to a position on the inner side of spring arm 14 and it is engaged by the spring arm and biased by it to a position where its inner end extends part way across slot 16. This position of the locking finger and spring arm 14 is shown in dotted lines in Fig. 2, the position being fixed by the back surface of the locking finger engaging the inner end of slot 23 which forms a stop for it. As shown in Fig. 2, the front surface of locking pin 24 is curved as indicated at 25.

To insert a lamp in a pair of holders 3 and 5 as shown in Fig. 1, one lamp end contact pin is inserted through the opening in housing 6 of lampholder 3 into engagement with contact arm 7 after which the contact pin at the other end of the lamp is pushed into lampholder 5 through

slot 16. In passing into slot 16, the contact pin first engages the curved surface 25 of finger 24, turning the finger against the spring action of arm 14 and moving the inner end of the finger out of the slot, the pin passing down beyond the locking finger into engagement with its seat 20. As soon as the pin moves beyond the end of the locking finger, spring contact arm 14 moves the end back into slot 16 in a position over the pin as shown in full lines in Fig. 2, the movement being limited by arm 14 engaging the contact pin. This serves to lock the contact pin in the lampholder.

To remove a lamp from the lampholder, the locking finger is engaged by a finger of the hand after the manner indicated in Fig. 5 and turned to bring its inner end out of slot 16. The lamp end will then drop out of or may be then moved out of the lampholder by use of the thumb as indicated in Fig. 5 and at the same time the lamp grasped by the hand and pulled free of lampholder 3. This is a simple operation and is especially advantageous where the lampholders are ceiling mounted and faced downwardly. To be able to remove a lamp from the holder by the use of only one hand is an important safety factor for the lamp replacer. At the same time finger 24 serves to lock the lamp end in the lampholder so it cannot accidentally fall out, a thing which may occur when lamps are ceiling mounted and the ceiling is subject to vibration.

A feature of my invention resides in the use of one of the spring contact arms of the lampholder for biasing the locking finger to locking

position. By this means my invention may be embodied in a lampholder by merely the provision of the pivoted locking finger, a thing which can be done at low cost; and since the locking finger is formed from a suitable insulating material, no exposed live part results.

What I claim as new and desire to secure by Letters Patent of the United States is:

In a lampholder, a housing having a slot at one end through which a contact pin on the end of a tubular lamp may be inserted, a pair of contact arms in the housing having spaced free ends adjacent and in alignment with said slot and shaped to define a seat for holding a tubular lamp contact pin, one of said arms being biased toward the other arm and having an end which projects beyond said seat, and a locking finger pivotally mounted at the edge of said slot having an inner end which projects into the slot and into engagement with the inner side of said projecting contact end and is biased by such contact end to a position where it projects partially across the slot, the outer end of said finger projecting beyond the lampholder housing to provide an actuating end for turning the finger.

JOHN M. PISTEY.
